ACETYLENE GAS GENERATORS

Fucheon T. Chen, Kowloon, Hong Kong

Application May 16, 1952, Serial No. 288,139

7 Claims. (Cl. 48—27)

1

This invention relates to acetylene generators for use with acetylene lamps.

In known constructions of generators for acetylene lamps, the feeding of water into the carbide compartment has been effected under atmospheric pressure and consequently whenever the pressure created by generation of gas in the carbide chamber is greater than atmospheric pressure to which is added the pressure of the column of water in the water chamber, acetylene gas will escape by bubbling out through the water. This gives rise to objectionable odours and may cause accidents by an accumulation of gas. Moreover, the adjustment of uniform illumination at various degrees is not only impossible but the maintenance of the illumination may not be possible without constant care or adjustment of the water controlling valve.

The object of the present invention is to provide an improved acetylene generator in which the objections above set out are eliminated.

According to the invention, the water and carbide compartments are connected by vent tubes by which the generated gas may pass from the carbide compartment to the water compartment, the water compartment being connected by a siphon tube to an air compartment, whereby water will be forced through said siphon from the water compartment should the pressure of the generated gas exceed atmospheric pressure to a predetermined degree and will return to the water compartment when the pressure of the gas falls slightly below the predetermined pressure.

In the accompanying drawings:

Figure 1 is a sectional elevation of an acetylene generator according to the invention.

Figure 2 is an outside elevation.

Figure 3 is a plan.

In carrying the invention into effect according to one convenient mode by way of example, the acetylene generator comprises a lower part 1 forming a carbide compartment and an upper part 2 which at the lower end 3 is of circular shape to conform with part 1. The parts 1 and 2 are detachably fixed together each part being inwardly flanged at 4 and 5 respectively. Between the flanges a rubber ring 6 is provided to form a gastight joint. The parts are secured together by screw means comprising a hollow threaded sleeve 7 and a complementary nut 8. The sleeve 7 and the nut 8 are mounted respectively on rings 9 and 10 soldered or welded to the flanges 5 and 4. The rings 9 and 10 are connected to their respective parts 1 and 8 by radial arms 11 and 12.

2

A loose base 13 is provided in the carbide compartment such base being supported by coiled springs 14 and 15. The springs act to disturb the carbide powder.

5 In the lower zone of the upper part 2 a valve block 16 is provided which is formed with a controlled passage 17 for acetylene and a controlled passage 18 for water.

The gas passage 17 opens to a pipe 19 for the 10 passage of gas to a burner 20. This passage is controlled by a gas valve 21 extending through a bore 22 in the valve block 16 and is threaded into the nut member 23. The gas valve is provided with a manipulating knob 24. The bore 22 communicates with a downwardly extending pipe 25 which passes through the sleeve 7 and into an enclosing tube 52 mounted on the springs 14, 15 and extending to a low level in the carbide compartment 1.

15 Oppositely disposed to the gas valve a water controlling valve 26 is located in a bore 27 in the valve block 16 which communicates with the water passage 18. The valve 26 is threaded into the nut member 28 and is provided with a manipulating knob 29.

The passage 18 opens into a recess 30 in the valve block 16 which passage is in communication with the carbide compartment 1. Above the bore 27 the valve block 16 is formed with a flange 31 defining a water transfer chamber 32 which communicates by a port 33 with the bore.

The water transfer chamber 32 is of relatively 20 small capacity and its upper end is open to chamber 39 through an aperture in a partition 35 which extends across and forms a lower wall to the upper part 2. Said upper portion extends laterally in a curved wall 36 and at the greater lateral dimension is divided by a partition 37 into an upper water reservoir 38 and a lower gas reservoir 39. The partition 37 is provided with a depression at 40.

25 Into the depression the ends 41, 42 of a pair of siphon pipes 43, 44 extend. The other end of siphon 44 extends into the water transfer compartment 32. The other end 43 of siphon pipe 43 extends into and to the lower end of an air compartment 46. Also extending through the partition 37 is a vent pipe 47 the lower end of which is open to the water transfer compartment 32 while its upper end is located above the normal water level in the water reservoir 38.

30 Communication between the carbide compartment 1 and the gas reservoir 39 is effected by a vent pipe 48 extending through the partition 35. The pipe 48 extends slightly below the level of the partition 37.

35

The water compartment 33 is provided with a filling pipe 49 with a gas tight screw cap 50.

The air chamber 46 is secured to the generator casing by a supporting band 51, the chamber 46 being a shape suitable to use it as a handle.

In operation, the carbide compartment being about two-thirds full of carbide, and the water compartment being filled to the lower end of pipe 49, a small quantity of water will flow through 10 syphon 44 to the water transferring compartment 32.

When the water valve 26 is open water will drop into the carbide compartment with consequent production of acetylene.

Gas generated in the carbide compartment 4, 15 going into the gas reservoir through vent 48 may pass into the water transfer chamber 32 then through vent 47 to the water reservoir when the lower end of vent 47 is uncovered.

When the pressure of the gas is higher than 20 atmospheric in addition to the weight of the column of water in compartment 33, the small quantity of water in the space 27 and in the compartment 32 will be forced into the syphon tube 44. If the pressure rises a further amount, water will 25 be forced through the syphon tube 43 into the air compartment 46.

When the pressure of the gas is reduced by 27 lighting the burner 28, water will return to space 20 and will drop through the valve passage 43 onto the carbide.

Should water rise from the space 27 and cover the lower end of the vent pipe 47 water will cease 30 to flow from the water reservoir 33. When the end of vent tube 47 is again uncovered the pressure of the gas in all compartments becomes equal whereupon the additional weight of the water in the water reservoir causes transfer of water onto the carbide.

The delivery water through the water valve is 35 uniform and constant irrespective of the size of the drop and the difference in the frequency of delivery by the regulating of the water valve in accordance with the pressure suitable for the intensity of illumination. The flow of water is also 40 automatic whatever the predetermined pressure.

The provision of the gas reservoir 33 ensures a steady flame.

By means of the springs 44 and 45 powder 45 accumulating over the decomposed carbide is shaken off, assuring immediate contact of water with the carbide.

Means may be provided whereby when the lamp is not in use and the gas valve 21 is closed, the lower end of vent pipe 43 is also closed so as 50 to avoid absorption of water vapour from other compartments through this vent and thus stop generation of acetylene.

It will be noted that acetylene is mainly drawn from the lower part of the carbide chamber so that the gas is filtered by the carbide itself and thus avoids water vapour passing over with the acetylene which may affect the illumination.

Although the improved generator has been described with reference to lighting it may be used 55 for heating or in the generation of power.

I claim:

1. An acetylene generator comprising a water reservoir compartment, a carbide compartment, a gas reservoir compartment, a water transfer chamber open to the pressure in the gas reservoir compartment, an air compartment, a siphon connection between said water reservoir compartment and said air compartment, a siphon connection between said water reservoir compartment and said water transfer compartment, a vent between said carbide compartment and said gas reservoir compartment, a vent between said water reservoir compartment and said water transfer chamber, and a valve controlled communication between said water transfer chamber and said carbide compartment, the arrangement being such that on the pressure of gas in said gas reservoir exceeding a predetermined amount, water will be forced through said siphon connecting said water reservoir compartment and into said air compartment, the water returning into said water reservoir compartment when the pressure is reduced below said predetermined pressure.

2. An acetylene generator as claimed in claim 1, wherein a valve controlled outlet for supplying gas to a burner communicates with the lower part of the carbide compartment by a downward depending pipe.

3. An acetylene generator as claimed in claim 1, wherein the carbide chamber is provided with a spring supported base for the carbide to shake off powder accumulating above the carbide.

4. An acetylene generator as claimed in claim 1, wherein the water reservoir compartment is provided with a filling inlet pipe, the lower end of which is positioned relatively to said siphon between said water reservoir compartment and the water transfer chamber so that only a small quantity of water flows through said siphon to said water transfer chamber.

5. An acetylene generator as claimed in claim 1, wherein said air compartment is secured to the side of the carbide compartment in spaced relation thereto and forms a handle therefor.

6. An acetylene generator as claimed in claim 1, comprising a casing formed in upper and lower parts detachably secured together by screw means, the lower part comprising the carbide compartment, the upper part having upper and lower cross partitions to form the water reservoir compartment and the gas compartment reservoir, and a space below the gas reservoir compartment accommodating a valve block housing said water control valve and said gas control valve.

7. An acetylene generator as claimed in claim 6, wherein the water control valve fitting is provided with an upstanding endless flange which engages the lower partition to form the water transfer compartment.
